UNITED STATES PATENT OFFICE.

AUGUSTUS J. ZANGERLE, OF BUFFALO, AND WILLIAM J. ZANGERLE, OF MOUNT MORRIS, NEW YORK.

SIGN.

Application filed October 31, 1927. Serial No. 229,827.

Our invention relates to improvements in signs, and more particularly to changeable signs for store or other display windows.

The primary object of our invention is the provision of a simple and inexpensive sign of this kind which has its body portion integral and preferably stamped of sheet metal and which is provided with means whereby cards are adapted to be interchangeably held.

Another object of our invention is the provision of a sign of the kind mentioned in which card receiving or display openings are formed in an integral metallic plate and retainer flanges provided for the cards which are struck up from the metal above and beneath such openings.

A further object of our invention is the provision of a sign of the kind mentioned, adapted to be secured to a store or other display window and having interchangeable cards bearing letters, figures, or other characters and arranged in horizontal rows spaced apart, and in providing the sign with openings between said horizontal rows of cards for the passage of light therethrough.

With the above and other objects in view, the invention consists in the novel features of construction and in the arrangement and combination of parts to be hereinafter described and more particularly pointed out in the subjoined claims.

In the drawings:

Fig. 1 is a front elevation of a sign constructed in accordance with our invention.

Fig. 2 is a central vertical section through the same showing the sign applied to the inner side of a store or other display window.

Fig. 3 is a horizontal section taken on line 3—3, Fig. 1.

Fig. 4 is a horizontal section taken on line 4—4, Fig. 1.

Fig. 5 is an enlarged vertical section through a portion of the sign for the purpose of better illustrating details of construction.

The reference numeral 6 designates the body portion of the sign, which is constructed from a flat and comparatively stiff sheet of metal cut to the desired size, depending on the size the sign is to be when finished. This sign may be varied in size, but for all practical purposes should be of

sufficient size to display a number of lines 55 of printed matter.

The sign is substantially rectangular and the marginal portions thereof are stiffened by curling the metal around a wire or wires 7, as at 8.

For the purpose of providing a finish to the upper end of the sign, a name plate 9 is riveted or otherwise secured thereto on which any desired matter may be embossed, cast, or otherwise applied.

Transverse card-receiving or display openings 10 are cut out of the body portion, and these are arranged in a vertical series, the openings extending almost from side edge to side edge of said body portion. If 70 desired, the lowermost card-receiving or display opening may be considerably larger than the remaining openings, but such arrangement is merely a matter of choice and depends considerably on the manufacturer 75 or the purpose for which the sign is to be used. These card openings 10, as they may be referred to, are arranged between openings 11, which are transversely coextensive with the card openings 10, and are separated 80 therefrom by transverse bars 12.

The metal displaced from the body portion 6 to form the card openings 10 is completely severed from the body portion and scrapped, while the metal displaced to form 85 the spacing openings 11 is utilized to form card retainer flanges 13.

The metal displaced to form the uppermost spacing opening 11 is bent rearwardly and downwardly upon the cross bar 12 directly beneath and spaced therefrom to form a card guide 14, while the metal displaced to form the lowermost spacing opening 11 is bent rearwardly and upwardly upon the cross bar 12 directly above and spaced therefrom to form a card guide 15. The metal displaced from the remaining spacing openings 11 is partly bent rearwardly and upwardly and partly rearwardly and downwardly, and for this purpose it must be slit 100 transversely and in a line centrally between the upper and lower edges of said spacing openings; the metal thus displaced forming the retainer flanges on the intermediate bars 12 to form card guides 16. The several retainer flanges 13 are arranged on the rear side of the body portion so that the front side, which is the side displayed through a

store or other window, indicated by the numeral 17, has a finished appearance.

By providing spacing openings between the card openings 10 and also above and beneath the series of said openings, light is allowed to pass through the sign and enter the interior of a store when the sign is secured to a store window. This we consider an important feature of our invention, particularly in respect to the manner in which these spacing openings are formed, as signs designed to be secured to store and like display windows, while considered desirable from the viewpoint of having an attractive location, are not commonly so used, due to the fact that they obstruct the passage of light into the interior of the store.

The guides 14, 15 and 16 are open at their ends, as at 18, so that cards 19 may be conveniently placed between two opposed retainer flanges disposed at opposite sides of each card opening, and these cards preferably contain a single letter or other character so that they may be arranged to form any desired word, or impart any desired information.

By making the lowermost card opening somewhat larger than the remaining card openings, a card of special size will be required for this opening, thus enabling a merchant using the sign to display the particular matter of interest in more attractive form. In the sign shown in the drawings the price is placed within the large card opening, whereas the particular article thus priced is disclosed by assembling cards to indicate the goods offered at such a price. The cards are easily removable so that the matter displayed may be changed as often as desired.

For the purpose of attaching the sign to a window, as indicated in Fig. 2, rubber suction cups 20 are secured to the body portion of the sign at the corners thereof, these being fastened to the sign in any approved manner. By moistening the window, or the edges of the cups, it is simply necessary to press these cups against the window, when the suction created therein, upon releasing pressure, will assure a secure fastening of the sign to the window. When fastened in place, the cards may be conveniently placed within the card guides formed by the retainer flanges 13 and they are as readily removable therefrom to permit of changing the sign without removing the same from the window.

Having thus described our invention, what we claim is:—

60 1. A sign having an integral body portion

provided with a vertical series of transversely elongated card openings, spacing openings between said card openings, transverse bars between said card and spacing openings having integral card retainer flanges, 65 the retainer flanges of the cross bars above and below each card opening being oppositely arranged, and an element bearing characters removably fitted between oppositely arranged retainer flanges and displayed 70 through said card openings.

2. A sign formed of a sheet of metal having card openings, spacing openings adjacent said card openings, and bars between said card openings and said spacing openings, each of said bars having an integral retainer flange along at least one of its edges formed from the metal displaced to form at least a part of one of said spacing 75 openings, and cards removably retained by the retainer flanges of said bars and displayed through said card openings.

3. A sign formed of a sheet of metal having transverse card openings, transverse spacing openings, and cross bars between said card openings and said spacing openings, each of said cross bars having integral retainer flanges along its upper and lower edges formed by material having been displaced from said sheet of metal to form said spacing openings, and cards removably inserted between said cross bars and their retainer flanges to be displayed through said card openings.

4. A sign having a body portion formed of a flat sheet of metal, a vertical series of card openings formed in said body portion, spacing openings transversely co-extensive with said card openings, said spacing openings being arranged above and beneath said series of card openings and also between said card openings, cross bars above and beneath each card opening and separating said card openings from said spacing openings, said cross bars having integral retainer flanges along their upper and lower edges formed by rebending the marginal portions thereof rearwardly and retaining such rebent portions in spaced relation thereto, said rebent portions having been displaced from said body portion to form said spacing openings, and cards bearing characters removably inserted in the spaces between said cross bars and their retainer flanges, said cards being displayed through said card openings.

In witness whereof we affix our signatures.

AUGUSTUS J. ZANGERLE.
WILLIAM J. ZANGERLE.
